FIG-1

FIG-2

FIG-3

FIG-4

FIGURE 1 is a perspective view of a portable chalk board or the like showing my new design;

FIGURE 2 is a side elevational view from one side thereof;

FIGURE 3 is a front elevational view thereof; and

FIGURE 4 is a top plan view thereof.

The rear elevational view of the portable chalk board or the like is substantially identical to the front elevational view of FIGURE 3. The side elevational view from the side opposite that of FIGURE 2 is a mirror image of the view shown in FIGURE 2.

I claim:

The ornamental design for a portable chalk board or the like, substantially as shown and described.
